PROCESS FOR TREATING MINERAL OILS

Merrell R. Fenske and Wilbert B. McCluer, State College, Pa., assignors to Pennsylvania Petroleum Research Corporation, a corporation of Pennsylvania

No Drawing. Application December 15, 1934,
Serial No. 757,732

4 Claims. (Cl. 196—13)

This invention pertains generally to the refining of petroleum oils and particularly to the refining of lubricating oils.

The invention pertains more particularly to the removal from lubricating oils, for instance, from oils of Pennsylvania grade, of undesirable substances such as color, Conradson carbon, wax and/or components of lower lubricating value.

As pointed out in our copending application, Serial No. 731,778, we have discovered that when a petroleum oil, and more particularly a lubricating oil, for instance, one of Pennsylvania grade, is fractionated by means of solvents, that is, separated into fractions which do not differ very materially in viscosity index, the color, Conradson carbon and/or wax or among the less soluble components and, therefore, concentrate in the undissolved portion of the oil.

We have also discovered in the solvent extraction of lubricating oil and particularly lubricating oil of Pennsylvania grade, to divide the oil into fractions respectively higher and lower in viscosity index, that smaller losses (of oil as extract) will occur if a given oil is divided into two or more cuts (differing chiefly as to molecular size or viscosity) prior to extraction than will occur if the overall oil is directly extracted. In other words, we have found that smaller quantities of extract need be separated from an oil to bring said oil up to a given viscosity index if cuts of said oil are separately extracted and the various raffinates are combined. Furthermore, the total quantity of extract decreases with the number of cuts, making it desirable from the standpoint of economy in oil to extract relatively narrow cuts.

The fractionation of the oil for the purpose of obtaining narrow cuts thereof may be accomplished by either fractional distillation or solvent fractionation.

For the purposes of this application the term "extraction" when used in connection with the separation of an oil into two or more parts will indicate that such separation is primarily for the purpose of producing oil fractions differing chiefly in viscosity index; that is, as to molecular type; the term "fractionation" will be used to indicate that such separation is primarily for the purpose of producing cuts differing chiefly in viscosity; that is, as to molecular size; the terms "extract" and "raffinate" will be used to indicate extraction products, and the term "cut" will be used to indicate a fractionation product.

As pointed out in said copending application, a monohydric aliphatic alcohol having more than four carbon atoms, such as secondary butyl alcohol, tertiary butyl alcohol, normal amyl alcohol, isoamyl alcohol, secondary amyl alcohol and secondary butyl carbinol, may be added to a petroleum oil and more particularly a lubricating oil, such as one of Pennsylvania grade, under

conditions conducive to the formation of two phases, and upon separation of the phases, it will be found that the oil in each phase will differ primarily as to viscosity and will not differ very materially in viscosity index. The color and Conradson carbon will concentrate in the undissolved oil phase. The data also show that wax will tend to concentrate in the undissolved oil phase. In other words, the undissolved cut will contain a higher percentage of color, Conradson carbon and/or wax than the dissolved cut. Thus, the dissolved cut will be in a higher state of refinement.

In the practice of this invention we now subject the undissolved cut to solvent extraction with any solvent or solvents suitable for this purpose and more particularly one which exhibits a high preferential solvent capacity for color and Conradson carbon.

Any process and/or apparatus known in the art may be employed for carrying out this step, as well as the previous step of fractionation.

Because of the relatively high concentration of color and Conradson carbon in the undissolved cut, when this cut is subjected to solvent extraction, relatively larger quantities of these undesirable components and relatively smaller quantities of desired oil components will go into the extract. Therefore, losses in desirable oil components may be very materially reduced.

It should be kept in mind that the undissolved cut is a fraction of the overall oil, and that when this cut is subjected to extraction, rather than the overall oil, savings are made in desirable oil components by virtue of this fact alone and in addition to the savings referred to in the previous paragraph.

The undissolved cut may have any desired boiling range. The boiling range will be determined by the amount of oil in the dissolved oil phase. If a relatively large quantity of oil is dissolved it will be obvious that the undissolved cut will have a narrower boiling range than it would have if smaller quantities of oil were dissolved.

Any other cut or cuts may also be subjected to solvent extraction if desired. These cuts may be made by any means known in the art, for instance, by fractionally precipitating a quantity or quantities of oil from the dissolved oil phase. Color, Conradson carbon and/or wax will be found in higher concentrations in the precipitated cut or cuts than in the dissolved cut.

The dissolved cut might also be subjected to solvent extraction, if desired, with or without (but preferably with) the prior removal of fractionating solvent therefrom.

The concentration of color and Conradson carbon in the heavier cut or cuts will greatly reduce the degree of or entirely eliminate extrac-

tion of the lighter cut or cuts according to requirements.

Solvents adapted for extraction purposes are 5 acetaldehyde, acetone, acrolein, allyl alcohol, allyl isothiocyanate, aniline, aniline oil, benzaldehyde, benzonitrile, beta beta dichlorethyl ether, butyl carbitol, cellosolve acetate, cresol, cresylic acid, crotonaldehyde, estersol, ethyl acetate, ethyl alcohol, ethylene chlorohydrin, furfural, furfuryl 10 alcohol, isopropyl alcohol, liquid sulfur dioxide, methyl acetate, methyl alcohol, methyl cellosolve, methyl thiocyanate, mixed toluidines, mononitronaphthalene, nitrobenzene, nitrotoluene, orthotoluidine, phenol, phenylacetate, phenylthiocyanate, 15 polyhydric alcohols, propionaldehyde, pyridine, tetrahydrofurfuryl alcohol, tolualdehyde, tolyl formate, tricresyl phosphate, xylidine, etc.

The higher concentration of wax in the heavier cut or cuts produced by the solvent fractionation 20 above referred to is, as a rule, not disturbed by solvent extraction of the cut or cuts with a solvent which is selective as to naphthenic constituents. This cut or cuts after extraction may be subjected to any suitable dewaxing process known 25 in the art and because of the high concentration of wax in this cut or cuts higher percentage amounts of wax may be removed than would be possible if the wax were not concentrated in said cut or cuts.

30 This makes it possible to either greatly reduce the degree of or entirely dispense with the dewaxing of the lighter cut or cuts according to requirements.

From the foregoing, it will be seen that a 35 petroleum oil, and more particularly a lubricating oil of Pennsylvania grade, may be divided into any desired number of cuts; that the heavier cuts will have a higher concentration of color, Conradson carbon and/or wax if the cuts are made by 40 solvent fractionation; that a higher percentage amount of color, Conradson carbon and/or wax may be removed with the same effort if the heavier cuts are treated rather than the overall oil; and that smaller losses of desirable lubricating components will occur if cuts of an overall oil are 45 separately extracted.

The term "solvent" in its broader phases includes any compound or plurality of compounds whether in the vapor, liquid or solid phase.

50 In the claims the term "lubricating oil" when referred to is intended to mean an oil of a viscous character that is of the order of 35 Saybolt seconds at 210° F. or above.

This invention is particularly useful in the refining of lubricating oils of Pennsylvania grade. 55 For instance, it is found to be much more economical in losses of oil as extract to separately extract wax distillate and cylinder stock or viscous neutral and bright stock than it is to extract a long residuum or a mixture of wax distillate and cylinder stock or a mixture of viscous neutral and bright stock.

Furthermore, it is found economical and expedient to first separate a long residuum by solvent fractionation into cuts corresponding to wax distillate and cylinder stock or viscous neutral and bright stock, as the case might be, for, by the use of solvent fractionation, color, Conradson carbon and/or wax is concentrated in the cylinder stock 60 or bright stock cuts which, in many cases, may alone be subjected to solvent extraction and/or

dewaxing, since the materials to be removed are concentrated therein. In any case, the lighter fractions require much less treatment, in view of the refining effected by the solvent fractionation step. 5

Moreover, the solvent fractionation step makes available for the first time the separate extraction of cuts of cylinder stock and bright stock since the latter stocks are ordinarily not separable by distillation without undue decomposition. 10

In the claims the term "Pennsylvania grade residuum oil" is intended to mean a residuum resulting from the distillation of a Pennsylvania grade crude oil, or of a fraction thereof containing relatively heavy components, or a Pennsylvania oil fraction of comparable viscosity obtained by solvent fractionation or any other fractionating means, or a product of such residuum other than a distillate thereof, and is employed generically to include a mixture of such residua. 15

While the invention has been particularly described, it is to be understood that this is by way of illustration and that changes, omissions, additions, substitutions and/or modifications may be 20 made without departing from the spirit of the invention which is intended to be limited only as required by the prior art.

We claim:

1. A process comprising separating wax containing lubricating oil into two fractions by means of solvent fractionation with a solvent selective chiefly as to molecular size to concentrate substances such as color, Conradson carbon and wax in the less soluble of said fractions, subjecting the less soluble of said fractions to solvent extraction with a solvent selective chiefly as to molecular type, dewaxing the raffinate thus produced, segregating the extract and wax thus obtained, and combining the remainder of said oil. 30

2. A process comprising separating wax containing lubricating oil into two fractions by means of solvent fractionation with a solvent comprising a monohydric aliphatic alcohol having at least four carbon atoms to concentrate color, Conradson carbon and wax in the less soluble of said fractions, subjecting the less soluble of said fractions to solvent extraction with a solvent selective chiefly as to molecular type, dewaxing the raffinate thus produced, segregating the extract and wax thus obtained, and combining the remainder of said oil. 40

3. A process comprising separating wax containing lubricating oil into two fractions by means of solvent fractionation with a solvent selective chiefly as to molecular size to concentrate wax in the less soluble of said fractions, subjecting the less soluble of said fractions to dewaxing, segregating the wax thus obtained, and combining the remainder of said oil. 55

4. A process comprising separating wax containing lubricating oil into two fractions by means of solvent fractionation with a solvent comprising a monohydric aliphatic alcohol having at least four carbon atoms to concentrate wax in the less soluble of said fractions, subjecting the less soluble of said fractions to dewaxing, segregating the wax thus obtained, and combining the remainder of said oil. 65
